UNITED STATES PATENT OFFICE.

RICHARD H. L. TALCOTT, OF BOSTON, MASSACHUSETTS.

MOUNT FOR PHOTOGRAPHS OR OTHER PICTURES.

SPECIFICATION forming part of Letters Patent No. 437,949, dated October 7, 1890.

Application filed September 30, 1889. Serial No. 325,492. (No model.)

To all whom it may concern:

Be it known that I, RICHARD H. L. TALCOTT, a citizen of the United States, residing at Boston, in the county of Suffolk and State of Massachusetts, have invented new and useful Improvements in Mounts for Photographs or other Pictures, of which the following is a specification.

This invention relates to mounts for photographs or other pictures, the object thereof being principally to provide appliances whereby pictures mounted on glass may be inclosed at their back and edges and to be capable of withdrawal and substitution at will without impairing the durability or appearance of the mounting appliance.

An object of the invention may otherwise be stated to be the provision of a mount for photographs and the like having many of the advantageous characteristics of the one described in Letters Patent of the United States granted to me March 23, 1886, No. 338,651, but which mounting appliances, owing to the construction thereof, may be supplied in quantities to users, rendering the work necessary to make the combination therewith of the picture very slight and easy of accomplishment by unskilled persons; and the invention consists in the construction and combination of parts, all as will hereinafter more fully appear, and be set forth in the claims, reference being had to the accompanying drawings, forming part of this specification, in which similar letters of reference indicate corresponding parts in all the views.

Figures 1, 2, and 3 are views in perspective of the parts of the inclosing-casing for the picture-glass separated, and also of the picture-glass. The part illustrated in Fig. 2 shows the rear side foremost. Fig. 4 is a cross-section of the mounted picture. Fig. 5 is a rear view of the mounting appliances placed and confined together. Fig. 6 is a central longitudinal section of the mounted picture. Fig. 7 is a front perspective view of the mounted picture, illustrating merely the general appearance thereof; and Fig. 8 is a sectional view similar to Fig. 6, but of a construction wherein, however, a somewhat more efficient mounting of the picture is insured at little greater labor.

The mounting appliances, according to this

invention, consist in part of a back piece A, of size and shape corresponding to that of the glass B, on which the picture a is mounted, 55 or to the picture itself, if comprised in a sheet or tablet of sufficiently thick and stiff material and not mounted on glass, said back being provided at three of its sides or edges with overturned edge pieces b secured at such 60 sides. The back piece may be formed of sheet metal and the turned-over edge thereof may be integrally formed; but it is preferred to form the back of a semi-rigid material—such as firm card or paste board—and to form the 65 edge pieces of a bowed or U form, (the cross-sectional contour of which is varying, according as to whether glass with its edge beveled or otherwise formed is employed,) and to secure them by their one side section to the 70 said back piece by gluing, riveting, or by both, or otherwise.

The mounting appliance, according to this invention, also consists in a removable cap C, of sheet metal or other suitable material, comprising the portion d, (see Fig. 2,) of bowed or U shape in cross-section, to overlie the end portion of the back piece, and to also overlie the edge of the picture-glass when in place, and said cap also comprises at its ends turned-over lips f to overlie the turned-over lips affixed to the sides of the main holder part.

A suitable catch device is to be applied between the back of the main holder part and the removable cap-section, whereby when the 85 picture has been inserted the cap will be effectually held in its place, and at x, Figs. 5, 6, and 8, one form of catch device is shown, which consists of forming on or affixing to the cap-section an eye g and providing on the 90 back A, near the open edge thereof, a pivoted hooked arm h to swing into and out of engagement with said eye, or instead of this very common form of catch device other well-known or approved securing devices may be 95 employed, and in large mounts more than one should be used.

A leg E is to be affixed to the back and holder portion, by which the mounted picture may be maintained in an upright position.

On desiring to remove the glass-plate B (having a picture thereon and visible at the front) from the mount, the catch device for

the cap-section is released, and on removing said cap-section the picture-glass may be withdrawn and a new one substituted therefor.

5 In Fig. 8 is represented the picture-sheet secured to the glass, bound all around the edge with strips *m*, of suitable impervious material, as cloth or leather, and by the provision of the said strips the picture is more effectually guarded against air and moisture and may be readily placed in the improved holder.

What I claim is—

1. A picture-mounting appliance consisting 15 of a main holder portion, comprising a back plate having an area corresponding to that of the picture to be mounted and having overturned lip portions on three of its edges and a removable cap portion rigidly affixed thereto, consisting of a **U**-shaped strip, also having at its ends angularly-extended **U**-shaped lip-continuations adapted to overlie the open extremity of said holder portion, and means, substantially as described, for confining the removable cap in place, substantially as described, and for the purpose set forth.

2. A picture-mounting appliance consisting 20 of a main holder portion, comprising a back plate of semi-rigid material having an area 25

corresponding to the picture to be mounted, provided with the metallic strips of **U** shape in cross-section securely affixed to three of the edges of said back plate, forming a bounding groove for said edges, and also provided with 35 a hinged leg, and a removable cap portion consisting of a **U**-shaped strip, also having at its ends angularly-extended **U**-shaped lip-continuations adapted to overlie the open extremity of said holder portion, and means, 40 substantially as described, for confining the removable cap in place, substantially as and for the purpose set forth.

3. The combination, with the holder portion comprising a back having substantially the 45 area of the picture to be mounted, and having overturned metallic lip portions rigidly affixed thereto on three of its edges, of a plate of glass having a picture cemented to its back and bound at its edges with impervious material, the removable cap portion, as described, and a catch device applied on and between said main holder and said removable cap portion, substantially as and for the purpose set forth.

RICHARD H. L. TALCOTT.
